SELECTIVE VENDING MACHINE

Arthur E. Siehrs, Chicago, Ill.

Application June 3, 1938, Serial No. 211,573

14 Claims. (Cl. 312—88)

This invention relates to coin controlled automatic vending machines, and particularly to automatic selective vending machines.

The object of this invention is to provide a machine which is adapted to vend packaged articles and particularly liquids in upright containers such as for example bottles of milk, and to provide the purchaser with a choice of flavors or brands of product in a single compact machine, so that a choice of at least two brands or flavors may be obtained.

Other objects relate to the common supporting and storing means for the merchandise, the segregation of their classes thereon, the means for selectively causing the desired article to be moved into delivery position, the automatic selective control means, the automatic coin actuation of the machine, the methods of preventing successive delivery of articles for a single coin, and the various methods and means by which the basic principles of selective operation and general common construction of the machine is retained while the details of operation are accomplished by modified means.

Further objects relate to the economy of operation and economy of storage capacity of the machine, and the various details of construction and arrangement of parts which will be apparent from a consideration of the following specification and the drawings, wherein:

Fig. 1 is a front elevation, with parts in section, and parts broken away of a typical vending machine embodying some of my selective vending principles.

Fig. 2 is a section on the line 2—2 of Fig. 1.

Fig. 3 is a fragmentary section on the line 3—3 of Fig. 2.

Fig. 4 is a wiring diagram of the electrical control circuits of the machine shown in Figs. 1 to 3.

Fig. 5 is a section similar to that of Fig. 2, embodying a modification thereof.

Fig. 6 is a section on the line 6—6 of Fig. 5.

Fig. 7 is a wiring diagram of the electrical control circuits of the modified construction shown in Figs. 5 and 6.

Fig. 8 is a section similar to that of Fig. 2 embodying another modified construction and a modified principle of operation.

Fig. 9 is a fragmentary section similar to Fig. 8 embodying a modification of the details thereof.

Fig. 10 is a wiring diagram of the electrical control circuits of the construction shown in Figs. 8 and 9.

Fig. 11 is a section similar to that of Figs. 2, 5 and 8 embodying still another modified con-

struction and another modified principle of operation.

Fig. 12 is a section on the line 12—12 of Fig. 11.

Fig. 13 is a detail section on the line 13—13 of Fig. 12 illustrating one position of the selective operating means of Fig. 11, and,

Fig. 14 is a similar view illustrating a detail of the selective operative means of Fig. 11 in a second position.

Fig. 15 is a fragmentary section similar to Fig. 11 embodying a modification of the details thereof.

Referring to Fig. 1 of the drawings, 10 indicates generally the housing of my selective vending machine, the general construction of which 15 is applicable to the various modifications thereof shown by the drawings and hereinafter described. The machine is conveniently divided into two compartments, the lower compartment 11 housing the gears, motor, refrigerating equipment, etc., 20 whereas the upper compartment 12 is provided with an inner body 13 so that insulating material 14 may be utilized. The top of compartment 12 is closed with a like insulated cover 15, thus providing a closed chamber insulated against heat 25 and cold, and which may thereby be more efficiently kept refrigerated to preserve the articles to be vended, particularly when they are perishable, such as milk.

Rotatably mounted within compartment 12 adjacent the base thereof is the turntable 16 which is adapted to support the merchandise to be vended such as the bottles 17 and 18, the table being provided with a downwardly depending collar 19 surrounding the shaft 20, and being supported in the bearing block 21 by the roller bearing 22 for ease in operation. Suitable means for rotating the turntable 16 are provided in the lower compartment 11, such as the motor 23 and the gears 24, 25 and 26, the latter being secured 40 to the collar 19. Within this compartment 11, although not shown, may conveniently be contained refrigeration equipment and the like appurtenances.

For convenience and conservation of space, a 45 trap door 27, having a diameter slightly larger than that of a single article to be vended, is formed on the base 28 of the compartment 12, adjacent a corner thereof when the machine is of rectangular construction, and is in substantially 50 osculating relationship with the turntable 16. Secured to the base 28 is the guide and retaining wall 29 which is substantially concentric with and spaced slightly outwardly of the table 16 for about three-quarters of its periphery, the re- 55

mainder of the wall 29 constituting the two tangential portions 30 and 31 which meet to embrace the trap door 27, the wall 29 being of sufficient height to retain the vendable commodities until delivery operation.

5 Fixedly secured to the axial shaft 20 and extending transversely over the table 16 are the pair of substantially curved deflecting arms 32 and 33 having their concavities toward each 10 other, their outer ends meeting at the periphery of the table 16 at the point where an extended radial line from the turntable bisects the trap door 27, or at the point of tangency of the discs forming the table and the trap door. These deflecting arms are of equal contour and arcuate 15 in shape for a substantial length, except for the portions forming their outward ends where they are straight and substantially parallel to the adjacent sides of the machine, so that these end 20 portions, together with the portions 30 and 31 of the guide walls form a pair of converging channels in a direction towards the trap door, of sufficient width to accommodate a single unit of the article to be dispensed. Extending radially and 25 transversely across the table from the axial shaft 20 to a point on the guide wall 29 diametrically opposed to the point of outer convergence of the deflecting arms 32 and 33, and fixedly secured at both of said points, is the dividing bar 34. It will 30 thus be seen that by means of the dividing bar 34 and the deflecting bars 32 and 33, which are of sufficient height to prevent an article on the table 16 from being carried over them, that the contents of the table 16 are kept separated into two 35 divisions, whereby they may be selectively vended as hereinafter set forth.

Selective vending of either of the articles 17 or 18 is accomplished by causing the table 16 to rotate either clockwise or counterclockwise. 40 Thus for example, if it is desired to vend an article 17, the table is caused to rotate clockwise, and the articles on the table between the guide wall 29, divider bar 34 and deflector arm 33, will be carried into the channel formed between the 45 outer end of arm 33 and the tangential guide wall portion 31 by the rotation of the table, by centrifugal force imparted to the articles, by guiding action of the arm 33, the convex curvature of which is opposed to the clockwise direction of 50 rotation of the table, and by the guiding action of the guide wall 29 and its portion 31, onto the trap door 27. The trap door is provided with a spring hinge 35 which permits the article 17 positioned on the trap door to drop through the opening 36 and onto a suitable cushion 37 contained in the delivery opening 38, from where it may be 55 manually withdrawn by the purchaser. Likewise, if an article 18 is desired, the table is caused to rotate counterclockwise.

60 The motor 23, which may be a 110 volt single phase motor, may be caused to reverse by means of a suitable reversal switch of a conventional type adapted therefor, and diagrammatically indicated at 39, which may be actuated by a purchaser by means of a lever 40 on the exterior of the machine. Thus the purchaser makes his selection of either of the classes of merchandise in the machine by turning the lever 40 to either one of the marked contacts 41 or 42. He then 65 places the requisite coin in the coin control box 43, which may be of any suitable type and which may include coin scanning and slug rejection means. The insertion of the proper coin closes the coin switch 44, the switch being preferably 70 of the type which remains closed after operation 75

by a coin until the circuit is broken at some other point, or if not thus broken will after a time limit return the coin and break itself. Other suitable means of holding the circuit closed after insertion of the coin until return thereof or delivery of the selected merchandise may be employed, such as for example, an auxiliary holding circuit. Thus insertion of a coin in the box 43 closes the coin switch 44 and permits the current to flow through either of the selected points 41 or 42 to operate 10 the motor 23, and cause the table 16 to rotate either clockwise or counterclockwise. As hereinbefore described, the rotation of the table in, for example, a clockwise direction causes the article 17 to be positioned on the trap door 27 whereupon 15 the weight of the article causes it to depress the trap 27 which is equipped on its under surface with a mercury trap switch 45 placed in the circuit. The lowering of the trap door operates the mercury switch to break the circuit and thus immediately stops the motor and resultant rotation of the table, and simultaneously re-opens the coin switch 44 which then remains open even though the article 17 is withdrawn and the trap door and its switch are then allowed to close by 20 means of the spring hinge. It will thus be seen that the trap door is cleared of its load and the subsequent operation of the machine may be either in the same direction or in the reverse direction, as controlled by the desires of the purchaser. It is of course to be understood that the electrical operation, circuit, switches and other like appurtenances may be suitably varied by 25 conventional means and devices.

Figs. 5, 6 and 7 are directed to a modification 35 of my selective vending principle, also embodying the use of a reversal switch to cause the supporting platform or turntable to rotate in two directions, in this modification, however, two separated trap doors are employed, and the contents 40 of each section of the retaining walls more positively separated. The construction and arrangement of the machine is generally the same as that set forth in Figs. 1 to 4.

In this modification, however, for economy of 45 space, the outer end portions 50 and 51 are curved in a direction reverse to the curvature of the deflecting arms 32' and 33' respectively, and after meeting at a point diametrically opposed to the point where the dividing arm 34' is joined to the 50 guide wall 29', continues outwardly to form a straight dividing portion 52 where it meets the retaining wall portion 53. On each side of the dividing portion 52 the trap doors 54 and 55 are formed on the base 28', the traps being in the 55 form of discs in osculating relation to the table 16', and of a sufficient diameter to receive the articles 17 or 18. The guide wall 29' substantially encompasses the table 16' but is provided with projecting portions 56 and 57 which are substantially parallel with the portion 52 and form a complete closure with the portion 53. The portions 56 and 57 meet the guide wall 29' at a curvature in the same direction respectively as the curved deflector bar portions 50 and 51, so that 60 they form therewith elbow channels into which an article on the table may be directed by rotation thereof as previously described, and thus an article 18 may be deposited on the trap door 54, or an article 17 may be deposited on the trap 65 door 55.

The trap doors 54 and 55 are respectively provided with tiltably operable mercury switches 58 and 59 or other like suitable circuit making and breaking means. In addition thereto the doors 70

are provided with the magnetic locks 60 and 61 interposed in the circuits made by the reversal switch 39', so that the trap doors are normally held closed by means of these magnetic locks 5 until a circuit in either direction is closed, at which time the lock opens. Thus if it is desired to purchase an article from, for example, the left hand side of the machine shown in Fig. 5, the reversal switch 39' is turned to the contact 41, and 10 a coin inserted in the machine which closes the switch 44'. This causes the lock 60 to open and the table 16' to rotate counterclockwise until an article 18 is positioned on the trap door 54, whereupon the article is delivered into the opening 62 15 and the mercury switch 58 becomes tilted to break the circuit and stops the motor. As soon as the article is withdrawn the trap door closes by means of its spring hinge 63, and the machine is ready for the succeeding sale. It is to be understood 20 that a single delivery opening 62 may be provided in the machine or two separate openings may be used, and that if desired they may be together or spaced apart, and that directional delivery chutes may be suitably employed.

25 The modified form of apparatus shown in Figs. 8, 9 and 10, while generally directed to selective vending and employing a revolvable merchandise supporting platform and a fixed segregation wall extending transversely thereover, accomplishes 30 selective vending by means other than reversal operation of the motor.

In this modification two trap doors, discs 80 and 81 in substantial osculating relationship to turntable 82 and diametrically opposed to each 35 other, are formed on the base 83. Substantially concentric with and extending around the turntable to include the trap doors is the retaining guide wall 84 secured to the base 83. Secured to the fixed axial shaft 85 and extending transversely across the table in opposed directions 40 therefrom are the curved deflecting arms 86 and 87 having respective outer terminal portions 88 and 89 curved in the reverse direction, so that together with the guide wall to which they are 45 attached, they form elbow channels, in a manner similar to those shown in Fig. 5, leading off in a radial direction.

Instead of conforming the wall 84 around the turntable and trap discs as close as possible, the 50 wall 84 may form a tangent to both the table and trap disc as at 90 in Fig. 9. In this detail modification, the outer end of the deflecting arms is then formed substantially parallel to the portion 90, as at 91 spaced apart therefrom to form a 55 tangential channel similar to that shown in Fig. 2.

For the operation of this machine selective operation is brought about by the use of two separate coin control boxes, the insertion of a coin in the selected box resulting in delivery of the selected 60 article. Thus coin insertion causes either of the coin switches 92 or 93 to close and causes either one of the magnetic locks 94 or 95 associated with the trap doors 80 and 81 to open, and simultaneously starts the motor 96. Although an 65 article 18 may be thereby positioned on the trap 80 and an article 17 on the trap 81 at the same time, due to the employment of the magnetic locks in the circuit of each coin switch, only the selected one will be opened. The trap doors 80 70 and 81 are also provided respectively with the tiltable mercury switches 97 and 98, whereby the motor circuit is broken when an article is positioned on a trap and allowed to drop downwardly.

Although not shown, it is apparent that with 75 this form of machine two spaced apart delivery

openings will ordinarily be required which may be formed on opposed or adjacent sides of the machine. It is also conceivable that a single delivery opening may be employed by adapting to the machine a second revolvable platform underneath the containing table, which will carry an article delivered from the remote side of the machine to a common opening on the front side thereof.

Figs. 11 to 15 set forth another modification of 10 my vending machine embodying the selective principle by means of a unidirectional motor operation as in the modified form of Figs. 8 to 10, but requiring the use of only a single trap door and delivery opening, the selective operation being 15 practically manually controlled.

In these Figures 11 and 12, the outer retaining wall 84' is similar to that shown in Figs. 9 and 8 respectively, with the exception that only one trap door 99 is embraced since only one is required. Further the curved arms 86' and 87' are loosely mounted by means of the hub or collar 100 on the shaft 85', or the collar may be secured to the shaft and the shaft adapted to freely revolve. The curved arms in this form of machine are at a 20 height above that of the wall 84'. The outward end portions of the arms, whether of the straight type of Fig. 11 or the partially curved type of Fig. 15, are elongated as at 101 and 102 to extend beyond the turntable 82' and the guide wall 84' and 25 over them, and the terminal portion being in the form of upwardly, or otherwise bent, abutting arms shown in detail in Figs. 13 and 14. Further each of these arm end portions are at spaced apart 30 elevations.

Extending through suitable journals 103 and 104 in the front of the machine are the selector rods 105 and 106 provided with suitable handles 107 and 108 on the outer side of the machine. These two selector rods extend inwardly for equal 40 lengths and terminate in stop links 109 and 110 respectively, fixed to them.

The operation of this machine requires a single coin box of the type hereinbefore described and a single circuit breaker in connection with the trap door 99, such as the mercury switch heretofore utilized. Otherwise no magnetic door lock or electrical selector arm is required. Prior to the insertion of a coin either selector handle is turned to the indicated position for selection, they being 45 adapted to be returned to a neutral position when not in use so that the stop links will normally be vertically extended. When turned to the selective position either of the links 109 or 110 will be horizontally extended, whereupon a coin is then 50 inserted in the coin box to close the coin switch which in turn causes the motor to operate and revolve the turntable. The articles supported on the table, even though there be only a single item, will carry along the freely mounted arms 86' and 60 87' until either the end of portion 102 lodges against the horizontally extended link 109 as shown in Fig. 13, or the end of portion 101 lodges against horizontally extended link 110, dependent 65 upon the selection made. This will cause the transversely extending curved arms to become 70 fixed to form guiding channels as in Fig. 11 or 15. If for example an article 18 has been selected, and the extended arm portion 102 has been stopped by the link 109, as shown in Figs. 11 and 75 15, the turntable which continues to rotate urges an article 18 forward and off the table and onto the delivery opening and by means of the trap switch breaks the circuit and stops the motor.

With this latter form of device it will be obvious that two or more divider or deflector arms may be employed to form two or more divisions so that selection may be extended beyond the two divisions shown by employing two or more selector stop arms, only a single coin box and delivery opening being required.

While I have set forth a number of modifications of my selective vending machine and described the parts and methods of operation thereof in detail, it will be apparent to one skilled in the art that further modifications may be made in the general structure and in the detailed parts and their arrangement without departing from the spirit of my invention; and I therefore do not wish to be restricted thereto except as so limited by the appended claims.

I claim as my invention:

1. A selective vending apparatus comprising a turntable adapted to support a plurality of classes of commodities in individual containers to be dispensed, a base substantially level with said turntable and extending outward of the periphery thereof, a delivery chute depending from the level of said base and having its entrance adjacent to the periphery of said turntable, a guide and retaining rim extending upwardly from said base around said turntable and embracing the chute entrance and separator means extending transversely above and over said turntable from adjacent the center thereof adapted to hold each contained class of commodity in segregated relationship, said separator means comprising a plurality of substantially arcuate deflector arm portions each adapted to cooperate with adjacent portions of said guiding rim to form a channel therewith and to successively and selectively guide the containers on the turntable during rotation thereof and to move them outwardly therefrom through said channels into said delivery chute.

2. A selective vending apparatus comprising a turntable adapted to support a plurality of classes of commodities in individual containers to be dispensed, means for rotating said turntable, a base substantially level with said turntable and extending outward of the periphery thereof, a delivery chute depending from the level of said base and having its entrance adjacent to the periphery of said turntable, a guide and retaining rim extending upwardly from said base around said turntable and embracing the chute entrance, and separator means extending transversely above and over said turntable adapted to hold each contained class of commodity in segregated relationship, said separator means comprising a plurality of deflector arms, each having portions extending from the axial shaft of said turntable arcuately to a point adjacent the periphery thereof and formed with terminal portions extending to the periphery thereof, the said terminal portions being parallel to adjacent portions of the guide rim, the said deflector arms and the component portions thereof being adapted to cooperate with said guide rim to form channels therewith to successively and selectively guide the containers on the turntable during rotation thereof and outward movement therethrough to said delivery chute.

3. A selective vending apparatus comprising a turntable adapted to support a plurality of classes of commodities in individual containers to be dispensed, coin controlled means for rotating said turntable, a base substantially level with said turntable and extending outward of the periphery thereof, a delivery chute depending from the level of said base and having its entrance adjacent to

the periphery of said turntable, a guide and retaining rim extending upwardly from said base around said turntable and embracing the chute entrance, and separator means extending transversely above and over said turntable from adjacent the center thereof adapted to hold each contained class of commodity in segregated relationship, said separator means comprising a plurality of deflector arm portions each adapted to cooperate with said guiding rim to successively and selectively guide the containers on the turntable during rotation thereof and to move them outwardly therefrom into said delivery chute, the said chute having means positioned therein adapted to discontinue rotation of the turntable upon delivery thereto of a container.

4. A selective vending apparatus comprising a turntable adapted to support a plurality of classes of commodities in individual containers to be dispensed, selective means for rotating said turntable in a clockwise and counterclockwise direction, a base substantially level with said turntable and extending outward of the periphery thereof, a delivery chute depending from the level of said base and having its entrance adjacent to the periphery of said turntable, a guide and retaining rim extending upwardly from said base around said turntable and embracing the chute entrance, and separator means extending transversely above and over said turntable adapted to hold each contained class of commodity in segregated relationship, said separator means comprising a plurality of deflector arms, each having portions extending from the axial shaft of said turntable arcuately to a point adjacent the periphery thereof and formed with terminal portions extending to the periphery thereof, the said terminal portions being parallel to adjacent portions of the guide rim, the said deflector arms and the component portions thereof being adapted to cooperate with said guide rim to form channels therewith to successively and selectively guide the containers on the turntable during rotation thereof and outward to said delivery chute.

5. A selective vending apparatus comprising a turntable adapted to support two separated classes of commodities in individual containers to be dispensed, selective means for rotating said turntable in a clockwise or counterclockwise direction, a base substantially level with said turntable and extending outward of the periphery thereof, a delivery chute depending from the level of said base and having its entrance adjacent to the periphery of said turntable, a guide and retaining rim extending upwardly from said base around and embracing the turntable and chute entrance, and fixed guide and separator means extending transversely above and over said turntable adapted to hold each class of commodity in segregated relationship comprising a pair of oppositely bowed deflector arms extending from the axial shaft of said turntable to a meeting point adjacent the periphery thereof and a divider arm extending from the axial shaft of said turntable to said guide rim at a point spaced from the outer meeting point of said deflector arms, the said deflector arms being adapted to cooperate with adjacent guide rim portions to successively and selectively guide the containers on the turntable during rotation thereof and to move them outwardly therefrom into said delivery chute.

6. A selective vending apparatus comprising a turntable adapted to support two separated classes of commodities in individual containers

to be dispensed, selective means for rotating said turntable in a clockwise or counterclockwise direction, a base substantially level with said turntable and extending outward of the periphery thereof, a delivery chute depending from the level of said base and having a common entrance adjacent to the periphery of said turntable in tangential relation thereto, a guide and retaining rim extending upwardly from said base around said turntable and embracing the turntable and chute entrance, and fixed guide and separator means extending transversely above and over said turntable adapted to hold each class of commodity in segregated relationship comprising a pair of oppositely bowed deflector arms extending from the axial shaft of said turntable to meet at a point of said tangential relation and a divider arm extending from the axial shaft of said turntable to said guide rim at a point spaced from the outer meeting point of said deflector arms, the said deflector arms being adapted to cooperate with adjacent guide rim portions to successively and selectively guide the containers on the turntable during rotation thereof and to move them outwardly therefrom into said delivery chute.

7. A selective vending apparatus comprising a turntable adapted to support two separated classes of commodities in individual containers to be dispensed, selective means for rotating said turntable in a clockwise or counterclockwise direction, a base substantially level with said turntable and extending outward of the periphery thereof, a delivery chute depending from the level of said base and having two entrance doors adjacent to the periphery of said turntable, a guide and retaining rim extending upwardly from said base around and embracing the turntable and chute entrance doors, and fixed guide and separator means extending transversely above and over said turntable adapted to hold each class of commodity in segregated relationship comprising a pair of bowed deflector arms extending from the axial shaft of said turntable to a meeting point adjacent the periphery thereof and radially outward to said retaining rim, and a divider arm extending from the axial shaft of said turntable to said guide rim at a point diametrically opposed to the outer meeting point of said deflector arms, the said deflector arms being adapted to cooperate with adjacent guide rim portions to successively and selectively guide the containers on the turntable during rotation thereof and to move them outwardly therefrom into said delivery chute.

55 8. A selective vending apparatus comprising a turntable adapted to support two separated classes of commodities in individual containers to be dispensed, selective means for rotating said turntable in a clockwise or counterclockwise direction, a base substantially level with said turntable and extending outward of the periphery thereof, a delivery chute depending from the level of said base and having two entrance trap doors adjacent to each other and to the periphery of said turntable, a guide and retaining rim extending upwardly from said base around and embracing said turntable and said trap doors, and fixed guide and separator means extending transversely above and over said turntable adapted to hold each class of commodity in separated relationship comprising a divider arm extending radially from the axial shaft of said turntable to said rim and a pair of bowed deflector arms extending from said axial shaft and converging towards each other at a point adjacent the per-

iphery of said turntable and extending outwardly therefrom and between said trap doors, the said deflector arms and component portions being adapted to cooperate with adjacent rim portions and to successively and selectively guide the containers on the turntable outwardly therefrom onto said trap doors.

9. A selective vending apparatus comprising a turntable adapted to support a plurality of classes of commodities in individual containers to be dispensed, means for rotating said turntable, a base substantially level with said turntable and extending outward of the periphery thereof, single container outlets comprising trap doors in said base positioned adjacent the periphery of said turntable, a guide and retaining rim extending upwardly from said base around said turntable and embracing the trap doors, separator means extending transversely above and over said turntable from adjacent the center thereof adapted to hold each contained class of commodity and an outlet therefor in separated relationship, said separator means comprising a plurality of deflector arm portions each adapted to cooperate with said guiding rim to successively guide the containers on the turntable during rotation thereof and to move them outwardly therefrom onto said trap doors, and means for selectively actuating said trap doors to deliver a single selected commodity through its respective outlet.

30 10. A selective vending apparatus comprising a turntable adapted to support a plurality of classes of commodities in individual containers to be dispensed, means for rotating said turntable, a base substantially level with said turntable and extending outward of the periphery thereof, single container outlets provided with trap door entranceways formed in said base adjacent the periphery of said turntable, a guide and retaining rim extending upwardly from said base around said turntable and embracing the trap door entranceways, separator means extending transversely above and over said turntable adapted to hold each contained class of commodity and respective entranceway outlet in separated relationship, said separator means comprising a plurality of fixed deflector arms, each having portions extending from the axial shaft of said turntable arcuately to a point adjacent the periphery thereof and formed with terminal portions extending to the guide rim, the said terminal portions being parallel to adjacent portions of the guide rim, the said deflector arms and the component portions thereof being adapted to cooperate with said guide rim to form channels therewith to successively guide the containers on the turntable during rotation thereof and outward movement therethrough to delivery position on said trap doors, and means for selectively actuating said trap doors to permit delivery therethrough of a single selected commodity.

55 11. A selective vending apparatus comprising a turntable adapted to support a plurality of classes of commodities in individual containers to be dispensed, coin controlled means for rotating said turntable, a base substantially level with said turntable and extending outward of the periphery thereof, a delivery chute depending from the level of said base and having a trap door entrance therein positioned adjacent to the periphery of said turntable for each commodity, a guide and retaining rim extending upwardly from said base around said turntable and embracing each chute entrance, and separator means extending transversely above and over said turntable from

- 5 adjacent the center thereof adapted to hold each contained class of commodity in segregated relationship, said separator means comprising a plurality of fixed deflector arm portions each adapted to cooperate with said guiding rim to successively guide the containers on the turntable during rotation thereof and to move them outwardly therefrom onto their respective trap doors, the said chute having means positioned therein adapted to selectively actuate said trap doors, and means adapted to limit rotation of the turntable upon delivery thereto of a container.
- 10 12. A selective vending apparatus comprising a turntable adapted to support a plurality of classes of commodities in individual containers to be dispensed, means for rotating said turntable, a base substantially level with said turntable and extending outward of the periphery thereof, a delivery chute depending from the level of said base and having its entrance adjacent to the periphery of said turntable, a guide and retaining rim extending upwardly from said base around said turntable and embracing the chute entrance, and separator means extending transversely above and over said turntable adapted to hold each contained class of commodity in segregated relationship, said separator means comprising a plurality of freely revolvable deflector arms each having portions extending from the axial shaft of said turntable arcuately to a point adjacent the periphery thereof and formed with terminal portions extending outwardly thereof, and selector means adapted to engage one of said terminal portions to hold it fixed in spaced apart parallel relation to a complementary guide rim portion adjacent said delivery chute entrance, the said terminal portion and component arm thereof being adapted in said fixed relation to cooperate with said guide rim to form a selected channel therewith to successively guide a selected class of containers on the turntable during rotation thereof outwardly to said delivery chute.
- 15 14. A selective vending apparatus comprising a turntable adapted to support a plurality of classes of commodities in individual containers to be dispensed, means for rotating said turntable, a base substantially level with said turntable and extending outward of the periphery thereof, a delivery chute depending from the level of said base and having its entrance adjacent to the periphery of said turntable, a guide and retaining rim extending upwardly from said base around and embracing said turntable and the entrance of said delivery chute, separator means extending transversely above and over said turntable and said guide rim adapted to hold each class of contained commodity in segregated relationship on said turntable, said separator means comprising a plurality of spaced apart deflector arms freely pivoted axially of said turntable, each of said arms having a portion extending from its pivot point arcuately to a point adjacent the periphery of the turntable and a terminal portion extending outwardly of said guide rim, and manually operable selector means adapted to engage one of said terminal portions to hold it fixed in spaced apart parallel relation to a complementary guide rim portion adjacent said delivery chute entrance, the said terminal portion and component arm thereof being adapted in said fixed relation to cooperate with said guide rim to form a selected channel therewith to successively guide a selected class of containers on the turntable during rotation thereof outwardly to said delivery chute.
- 20 13. A selective vending apparatus comprising a turntable adapted to support a plurality of classes of commodities in individual containers to be dispensed, means for rotating said turntable, a base substantially level with said turntable and extending outward of the periphery thereof, a delivery chute depending from the level of said base and having its entrance adjacent to the periphery of said turntable, a guide and retaining rim extending upwardly from said base around said turntable and embracing the chute entrance, separator means extending transversely above and over said turntable adapted
